(57) **CLAIM**

The ornamental design for a chili-shaped automobile hanging ornament, as shown and described.

DESCRIPTION

FIG. 1 is a front, perspective view of a chili-shaped automobile hanging ornament of the present invention.

FIG. 2 is a left elevation view thereof;

FIG. 3 is a back elevation view thereof;

FIG. 4 is a right elevation view thereof; and

FIG. 5 is a front elevation view thereof;

FIG. 6 is a top plan view thereof; and,

FIG. 7 is a bottom plan view thereof.

The broken lines shown in the drawings represent unclaimed portions of the design and form no part thereof.
